[57] CLAIM

The ornamental design for a support stand for a desk
telephone, as shown and described.

DESCRIPTION

FIG. 1 is a left side, top and rear perspective view of a
support stand for a desk telephone showing my new
design;

FIGS. 2 and 3 are respectively rear and front eleva-
tional views thereof;

FIG. 4 is a top plan view thereof;

FIG. 5 is a left side elevational view thereof, the side
opposite being a mirror image thereof; and

FIG. 6 is a bottom plan view thereof.

FIG. 1

FIG. 2

FIG. 3
